UNITED STATES PATENT OFFICE.

CLYDE NELSON JUSTICE, OF GREENSBORO, NORTH CAROLINA, ASSIGNOR TO JUSTICE
MANUFACTURING COMPANY, A CORPORATION OF NORTH CAROLINA.

MOP.

Application filed February 7, 1924. Serial No. 691,267.

To all whom it may concern:

Be it known that I, CLYDE N. JUSTICE, a citizen of the United States, residing at Greensboro, in the county of Guilford and State of North Carolina, have invented certain new and useful Improvements in Mops, of which the following is a specification.

This invention relates to an improvement in mops of the type particularly adapted for 10 dusting or polishing floors, or other surfaces.

To that end the invention contemplates a simple and practical construction providing a strong and rigid mop frame which is adapted to carry a plurality of circular thrums which are firmly and effectively held 15 in position to form a very full or super-abundant mop-body.

A further object of the invention is to provide a frame having novel means for 20 attaching the mop body to the head of the mop-stick.

With the above and other objects in view which will more readily appear as the nature of the invention is better understood, 25 the same consists in the novel construction, combination and arrangement of parts, hereinafter more fully described, illustrated and claimed.

A preferred and practical embodiment of 30 the invention is shown in the accompanying drawings, in which:

Figure 1 is a perspective view of the improved mop.

Figure 2 is a perspective view of the mop 35 frame illustrating the manner in which the circular strands are held in place.

Similar reference characters designate 40 corresponding parts throughout the several figures of the drawings.

In carrying the invention into effect it is proposed to provide a construction which is primarily intended for use as a dry mop. That is, a mop used for dusting and polishing purposes as distinguished from a wet 45 mop which is usually used in washing and scrubbing, instead of the lighter operation of removing dust, lint and the like from the floor surface. In that connection it is desirable to provide a mop having a rather substantial and strong frame and which is capable of carrying a super-abundant quantity of thrums so as to give an adequate cushioning effect to the mop and prevent scratching 50 of floors, furniture and the like.

Accordingly, the present invention proposes to employ a main frame designated generally as 1 for receiving and carrying the mop material M and which consists of a plurality of circular fabric thrums 2, the same being locked to the frame in the manner shown in Figure 2 in such a way as to firmly and securely hold them in place. 55

The manner of making the mop body in general which consists of the frame 1 and the thrums 2, is one of the important and distinctive features of the present invention. That is to say, the thrums 2 which are circular pieces or loops of fabric, usually a waste product of hosiery and like knitting mills, are placed between two strands of wire 60 3 and 4 and crowded thereon in numbers, thereby providing super-abundant quantity of circular strands between the wires 3 and 4. When the wires 3 and 4 are twisted in 65 the manner shown in Figure 2 the said circular loop-like thrums 2 become firmly locked in place and completely encircle and encase the frame consisting of the wires 3 and 4 as shown in Figure 1. 70

It will therefore be apparent that by placing a super-abundant quantity of the circular thrums between the wires 3 and 4 they will loosely fall over and about, and surround the wire frame because of their soft and flexible character, and thereby completely encase and envelope it and prevent it from scratching highly polished or finished surfaces. In Figure 2 the thrums 2 have been very much reduced in number simply to illustrate the manner in which they become 75 locked with the wire when it is twisted, but it is desired to emphasize that as many strands 2 are employed between each one of the twists on the wire as can possibly be crowded into the available space. In that 80 way the effect of completely enveloping and encasing the wire is obtained as illustrated in Figure 1. 85

A further distinctive and practical feature of the invention resides in the provision of the cross-bar 5 which may be attached as at 5^a to the main frame 1. In the illustration shown the cross-bar 5 is in the nature of a diametrical member extending across the circular frame 1. However, it will of course 100 be understood that the main frame 1 may assume a rectangular, triangular or other form than circular by simply bending the 105

same into the desired shape. Nevertheless, the cross-bar 5 in every case will serve to assist in bracing the structure and at the same time provide means for securing an attaching tab 6 in position.

The said attaching tab preferably consists of a plurality of individual circular members 7 of the same character as the thrums 2 and may each be tied at their middle portion onto the cross-bar 5 as indicated at 8. In that way the free end portions may be securely held together by suitable rows of stitches 9 thereby leaving the closed ends of the circular members 7 at the upper end of the tab and presenting no raw or unfinished edges. Obviously, the tab 6 may be made of any desired number of strands 7 and thereby be made of any desired width, and in event the width of the tab is not equal to the length of the cross-bar 5 the latter may be encircled or enveloped by separate strands of fabric which may be wrapped thereabout as indicated at 11.

With this type of tab it will be seen that the mop may be readily and conveniently attached to any of the standard forms of mop clamps.

From the foregoing it will be apparent that the present invention aims to provide a mop consisting of a plurality of circular thrum elements which are crowded between a pair of wires constituting a main frame prior to the twisting of the latter in such a way as to form a casing for the wire and form a super-abundant body for the mop. Also the manner of bracing the frame and securing the attaching tab thereto is another feature of the invention which is found to be practical and useful in service.

Without further description it is thought that the features and advantages of the improvement will be readily apparent to those skilled in the art and it will of course be understood that changes in the form, proportion and minor details of construction, may be resorted to without departing from

the spirit of the invention or scope of the appended claims.

I claim:

1. A mop consisting of a looped main frame comprising separate wires having a plurality of endless circular thrums crowded thereon and locked to the frame by twisting the wires, a cross-bar secured to the frame, and a tab secured to said cross-bar adapted to be engaged by a mop holder.

2. A mop consisting of a body including a main frame and a fabric mop-body, a cross-bar carried by the frame, and a fabric attaching tab secured to said cross-bar and consisting of a plurality of individual circular members tied onto the cross-bar at their medial portions, and stitches for securing the members together.

3. A mop consisting of a looped main frame carrying a fabric mop body, a cross bar carried by the frame, and a flexible fabric tab secured to said cross bar and adapted to be engaged by a mop holder.

4. A mop consisting of a body including a main frame comprising separate wires and a plurality of separate individual, endless, circular fabric thrums crowded thereon and locked to the frame by twisting the wires whereby said thrums encase the frame and also provide a fabric mop body including a plurality of double strand thrums.

5. A mop structure comprising a frame member, a plurality of separate circular endless fabric elements mounted thereon in intimate contact with each other, and means cooperating with said frame member to secure the fabric elements thereon against relative movement along the frame member, said frame member and securing means being encased by the fabric elements.

In testimony whereof I hereunto affix my signature in the presence of two witnesses.

CLYDE NELSON JUSTICE.
